REMOVABLE OVEN VENT GRILLE FOR
ELECTRIC RANGES

Edwin H. Lockwood, Mansfield, Ohio, assignor
to Westinghouse Electric & Manufacturing
Company, East Pittsburgh, Pa., a corporation
of Pennsylvania

Application February 27, 1936, Serial No. 66,018

1 Claim. (Cl. 126—21)

This invention relates to cooking ranges and is particularly adapted to electric ranges.

It is an object of this invention to provide a ventilating means for the oven of such ranges.

5 It is a further object of this invention to so direct the ventilating duct that its opening into the room shall be away from the walls.

10 It is a further object of this invention to provide a closure for the exterior end of the ventilating duct which shall have openwork to afford ventilation.

15 It is a further object of this invention to provide means whereby the closure may be readily removed for cleaning or for access to the ventilating duct.

It is a further object of this invention to locate the exterior end of the duct in the back splasher.

20 Other objects of the invention and details of the construction will be apparent from the following description and the accompanying drawing, in which:

Figure 1 is a front elevational view of the range.

Fig. 2 is an end elevational view of the same.

25 Fig. 3 is an elevational view of the closure for the duct and

Fig. 4 is an edge view of the closure.

The range 1 has an oven 2 closed by a door 3. The top or cooking surface 4 of the range is 30 equipped at its back edge with an upright panel 5 which is the back splasher. It serves to protect the wall of the room from grease, smoke or other dirt produced during the cooking.

Inside of the oven an outlet 6 is provided 35 which extends into a duct 7. The duct 7 has its other end in the surface of the back splasher. A disk 8 closes the opening in the surface of the back splasher which is the end of the duct 7.

This closure is not tight, but is made in the 40 form of a grille or openwork. In the form shown, this grille consists of arched bars 9 which extend across the disk 8. The bars extend beyond the front surface of the back splasher as may be best seen in Figs. 2 and 4. If desired, any other form 45 of openwork may be used instead of the bars 9, and it is not necessary that they extend beyond or rise above the surface of the disk. At the circumference the metal of the disk is turned inwardly forming a flange as shown at 10 in Fig. 4, and at intervals around the circumference fingers 50 11 extend toward the rear of the back splasher. These fingers are arched outwardly as may best

be seen by observing the top and bottom fingers in Fig. 4. They frictionally engage the walls of the duct at its mouth and thus secure the closure in place.

In the operation of the device, the food to be 5 cooked is placed in the oven 2 and whatever vapors it produces in cooking emerge from the oven 6 into the duct 7 and thence through the openwork of the disk 8 into the room. Since this disk is on that surface of the back splasher 10 which is toward the working surface of the stove, the fumes from the oven are not directed against the wall of the room and consequently do not mark the wall. This is particularly important when through any accident the food in the oven 15 is charred and the smoke from the charring escapes through the disk. Not only does the smoke not mark the wall, but because it emerges directly into the room, the attention of the operator is quickly called thereto and she can attend to the material being cooked before serious 20 damage is done.

It will, at times, happen that the duct 7 becomes fouled with grease, soot or other dirt and must be cleaned. For this purpose the disk 8 is 25 removed from the mouth of the duct. The disk can then readily be cleaned and the duct is accessible, whereby the cleaning of it is more easily accomplished. When the disk is inserted into the mouth of the duct the fingers 11 are slightly bent 30 inward and their frictional engagement with the walls of the duct keeps the disk in place. The openwork 8 affords an engagement for the fingers or for a hook whereby the disk may be conveniently removed from the mouth of the 35 duct when necessary.

Although I have specifically described and illustrated one form of this invention, other forms will be obvious to those skilled in the art. I therefore do not intend the specific description 40 and illustration to act as a limitation. No limitations are intended except those expressly stated in the claim or required by the prior art.

I claim as my invention:

An openwork disc constituting a duct outlet 45 for insertion in a back splasher, said disc being dome shaped and having an inwardly extending flange at its edge, and spring fingers extending from the inner edge of said flange into said duct and frictionally engaging the walls thereof to 50 hold the disk in the mouth of said duct at the back splasher.

EDWIN H. LOCKWOOD.
